UPHOLSTERED FURNITURE

Frank Schlachta, Pittsburgh, Pa., assignor of
one-half to Andrew K. Sypien, Pittsburgh, Pa.

Application November 24, 1934, Serial No. 754,618

3 Claims. (Cl. 155—184)

This invention relates to upholstered furniture, such as davenport, sofas and chairs of the loose cushion seat type as used in living rooms, hotel lobbies etc.

In ordinary practice, furniture of this kind is provided with a cushion support, commonly called in the trade platform, having a plurality of helical springs which rest on its bottoms on a laced webbing. The tops of said helical springs are tied together with a strong twine, covered with a single piece of canvas and filled with moss and cotton and again covered with a single piece of canvas which is tacked to the rails of the chair or sofa. Before the top canvas is tacked to the side rails of the furniture the space between the two arms, the back and the platform is packed with moss or other suitable material, so that no gap exists between the platform and the arms and back.

In the above described construction, a great percentage of the flexibility of the springs near the arms and the back is lost, due to this compact packing. Another disadvantage of this construction is when, for instance one of the helical springs or the tie-cord breaks, the platform has to be entirely ripped open when replacing defective parts.

My invention relates particularly to improvements which overcome the disadvantages outlined above and the objects of my invention are as follows:

The primary object of my invention is to provide upholstered furniture such as chairs, divans etc. with a removable platform which is hingedly attached to the front rail of said chairs, divans etc.

Another object of my invention is to provide a platform in which all of the helical springs are uniformly resilient.

Yet another object of my invention is to provide a platform which readily permits inspecting or repairing of the helical springs, tie-cords etc. without ripping platform apart.

Still another object of my invention is to provide a platform which is automatically held in stretched position.

Another object of the invention is to provide upholstered furniture, such as chairs, divans, etc. in which the construction of the platform may be readily inspected before purchasing.

Still another object of the invention is to provide a platform of upholstered chairs, divans, etc. which permits easy cleaning, thus making such furniture clean, mothproof and therefore sanitary.

Still another object of the invention is to provide upholstered chairs etc. in which the full benefit of the helical springs is attained by eliminating the packing between the arms, the back and the platform.

Another object of my invention is to provide upholstered chairs etc. which are simple in construction and arrangement, strong and durable, efficient and convenient in use and inexpensive to manufacture.

With the foregoing and other objects in view this invention consists of the novel construction, combination and arrangement of parts, as hereinafter set forth and more specifically described and illustrated in the accompanying drawings wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a perspective general view of an upholstered chair illustrating the pad flapped over to expose the construction of the platform.

Figure 2 is a similar view as outlined above, showing the platform ready for the reception of a cushion.

Figure 3 is a perspective view of a cushion.

Figure 4 is a detail view of a rear corner of a chair or divan frame, showing the helical spring suspension and other details of the platform.

Figure 5 is a sectional side view of the lower part of a chair or divan in accordance with my invention.

Figure 6 is a sectional side view of a corner of a chair or divan frame, with parts eliminated and parts broken away; and

Figure 7 is a top view of the seat portion of a chair or divan frame illustrating the construction and arrangement of the platform as used in my invention, with parts eliminated and parts broken away.

In carrying out my invention, I provide a chair or divan frame 8, comprising the side rails 9, a front rail 10, a rear rail 11 and the legs 12.

At this time, it is important to mention that no change of the present method of constructing chair or divan frames is required when using my improvements, furthermore old upholstered chairs or divans may be readily altered or modified at low cost, without changing the structure of the conventional frame work of the same.

A series of helical springs 13 are placed in the

55

usual manner, resting on a laced webbing 14, which is tacked to the underside 15 of the railings 9, 10 and 11 as shown in the various views of the drawings. The bottom 16 of said coil springs 13 is securely fastened on said webbing 14.

The upper portions 17 of the outer helical coil springs 13 are connected at the edges by means of suitable connectors 18 to a stiff wire frame 19, which is of rectangular shape, similar to the shape of the seat frame 8 and is preferably rounded at the corners, to fit partly around the helical corner springs, as best shown in Figure 7 of the drawings. The said wire frame 19 is fully covered with canvas 20, which covering extends downwardly and is tacked to the upper edge 22 of the rails 9, 10 and 11 by means of tacks 21.

In order to prevent excessive forward swaying of the platform, the wire frame 19 is yieldingly held at the rear end by two sets of three coil springs, one at each corner, arranged in a manner as shown in Figures 4 to 6. The aforesaid arrangement comprises a pin-bolt 23, one end of which is pointed, as at 24, and the other end 25 is threaded.

25 This pin-bolt 23 is first inserted through the aperture 26 of the back-brace 27 and two coil springs 28 and 29 of proper proportions are slipped over the protruding end of said pin-bolt 23. The pin bolt 23 is then driven into the top 30 of the rear rail 11 and tightened by means of a nut 30.

Should it be desired to make the said springs 28 and 29 adjustable an additional nut 31 may be placed below the back-brace 27, as shown in Figure 6. Another coil spring 32 is hooked around the pin-bolt 23 between the coil springs 28 and 29 and fastened to the wire frame 19, in a manner as best shown in Figure 6.

A quilted pad 33, of similar outline as the seat 40 of the furniture and of uniform thickness with the exception of the two sides and the rear edge, is being employed in my invention and the underside of the front edge of said pad 33 is attached with tacks to the top portion of the front rail 45 34, so as to provide a hinged front end which will permit flapping over of said pad 33 when desired, as is clearly illustrated in Figure 5 of the drawings.

Referring now to Figures 1 and 5, pad 33 is 50 provided with thinned out edge portions 35 at three edges, so as to permit these edges to be conveniently pushed under the arms and the lower edge of the rear or back of the furniture by pressing downwardly upon the pad, thus, a 55 seal between said platform and the arms and the back of the furniture being effected when pad 33 is in its final position.

At each corner of the pad 33 I provide a metal ring 37 secured thereon (Figure 5) and underneath the back brace 27 in near proximity of the pin-bolt 23 I provide a small hook 39. When the pad is placed into final position as shown best in Figures 2 and 5, an elastic string 40 may be tied around said ring 37 and hook 39, this is to provide additional means to prevent the pad from wrinkling.

In order to conveniently remove said pad 33

when it is desired to clean or repair the inside of the platform, I provide a loop 36 which is sewed on the back edge of the pad as clearly shown in Figures 2 and 5. By taking hold of said loop 36 and by pulling frontwardly or towards the operator the pad 33 will be released from its hold under the arms and the lower end of the back of the furniture, thus exposing the elastic ties 40 due to its elasticity, and it is now possible to easily remove these ties from the hooks 39.

It is believed that the operation of the device will be readily understood, without a further detail description of such operation, in view of the purpose and function of the different elements 15 having been set forth previously. I only wish to add that the thinned out edge portions of the pad at the arms and back are pushed between the underside of the arms and back by depressing the helical coil springs with the palm of the hand. When released the said helical springs force the edges of the pad tightly against the underside of the arms and the back thus retaining the pad in a stretched position at all times.

25 I claim:

1. In an upholstered chair and the like comprising a substantially rectangular supporting frame, a platform mounted on said frame and including a plurality of seat-springs, side arms 30 and a back inwardly upholstered, a substantially rectangular padding covering said springs, said padding being permanently secured at its front edge to said frame, the other edges of the padding being free and tapered for ready insertion 35 and frictional engagement between the seat-springs and the upholstered side arms and back of said chair.

2. In an upholstered chair and the like comprising a substantially rectangular supporting 40 frame, a platform mounted on said frame and including a plurality of seat-springs, side arms and a back inwardly upholstered, a substantially rectangular padding covering said springs, said padding being permanently secured at its front 45 edge to said frame, the other edges of the padding being free and tapered for ready insertion and frictional engagement between the seat-springs and the upholstered side arms and back of said chair and means to releasably secure the 50 rear edge of said padding to said frame.

3. In an upholstered chair and the like comprising a substantially rectangular supporting frame, a platform mounted on said frame and including a plurality of seat-springs, side arms 55 and a back inwardly upholstered, a substantially rectangular padding covering said springs, said padding being permanently secured at its front edge to said frame, the other edges of the padding being free and tapered for ready insertion 60 and frictional engagement between the seat-springs and the upholstered side arms and back of said chair and unitary means to releasably secure the rear edge of said padding to said frame and resiliently hold the padding in taut 65 condition.

FRANK SCHLACHTA.
